UNITED STATES PATENT OFFICE.

FRANK B. HENRY, OF PHILADELPHIA, PENNSYLVANIA.

FLUID-MOTOR.

1,263,060.

Specification of Letters Patent. Patented Apr. 16, 1918.

Application filed March 22, 1917. Serial No. 156,579.

To all whom it may concern:

Be it known that I, FRANK B. HENRY, a citizen of the United States, residing at Philadelphia, in the county of Philadelphia and State of Pennsylvania, have invented new and useful Improvements in Fluid-Motors, of which the following is a specification.

My invention relates to new and useful improvements in fluid motors, and has for its object to provide an exceedingly simple and effective device of this character, into which is forced a motive or propelling element, such as compressed air, steam, gasolene or other fluid, the same traveling around through divers and circuitous passageways within the motor, whereby the latter is caused to revolve, the motive element finally issuing from the exhaust into a chamber 20 provided with a spiral, whereby additional power is produced for propelling the motor.

A further object of the invention is to provide a fluid motor comprising end walls or heads, the inner faces of which are radially corrugated, and between these heads are situated a plurality of radially corrugated partitions or plates forming annular zig-zag passageways, said passageways being further provided with transversely corrugated walls for dividing the zig-zag passageways into annular, concentric fluid canals, the canals between each pair of corrugated partitions having communication with corresponding adjacent canals, the outer walls of the outer fluid canals being formed by the angular projections carried by the sleeve or jacket. The motive element or fluid enters a steam chest through the hub of one of the end walls or heads, and from the steam chest enters the interior of the motor, passing into the first two sets of concentric fluid canals, and after passing around these canals enters an expansion chamber, from which it passes into the next adjacent set of concentric fluid canals, whereby it continues to pass through each successive set of fluid canals formed between adjacent pairs of corrugated partitions, and after passing through the last set of fluid canals it enters an exhaust chamber, from which it passes through

an exhaust pipe or nozzle into a conical outlet chamber situated on the outside of one of the end walls or heads, said outlet chamber having a spiral therein, thereby forming a spiral passageway by means of which the final power of the motive fluid is utilized before passing into the atmosphere.

With these ends in view, this invention consists in the details of construction and combination of elements hereinafter set forth and then specifically designated by the claims.

In order that those skilled in the art to which this invention appertains may understand how to make and use the same, I will describe its construction in detail, referring by numeral to the accompanying drawing forming a part of this application, in which—

Figure 1, is a side elevation of a fluid motor made in accordance with my improvement, a portion thereof being shown in section to illustrate the construction.

Fig. 2, is a section at the line 2—2 of Fig. 1.

Fig. 3, is a fragmentary section at the line 4—4 of Fig. 2.

Fig. 4, is a similar view of the opposite or exhaust end of the motor.

Fig. 5, is an enlarged section at the line 5—5 of Fig. 4.

Fig. 6, is a section at the line 6—6 of Fig. 1 on a reduced scale; and

Fig. 7, is an end view at the same reduction of the exhaust end of the motor, the supporting standard being removed.

In carrying out my invention as here embodied 2 and 3 represent the end walls or heads of the motor, the latter being the one situated at the exhaust end and the former the one at the entrance end, and this head 2 is provided with an integral hub 4, one end projecting outwardly from the head, and the other end projecting inwardly as shown in Fig. 1. In the outwardly projecting end of the hub is formed a fluid inlet 5, whereby suitable connection may be made therewith for the entrance of a suitable motive fluid, and this inlet opening communicates with the steam chest 6 carried by the head 2, pref-

erably formed integral therewith and projecting outwardly from the face thereof. Adjacent the steam chest 6 is formed an expansion chamber 7 and, if found desirable, 5 this chamber may also be formed integral with the head 2, a portion thereof projecting outwardly beyond the outer face of the head, and another portion projecting inwardly beyond the innermost line of said 10 head. The inner faces of the heads 2 and 3 are each corrugated or provided with angular ribs 8 arranged on radial lines, and the inner end wall of the expansion chamber 7 is similarly corrugated as at 9. The head 3 is 15 provided with an exhaust chamber 10 which may be formed integral therewith, if desired, and this chamber projects inwardly and outwardly from the head 3, and has its inner wall corrugated as at 11.

20 Between the end walls or heads 2 and 3 are arranged a plurality of radially corrugated partitions 12 arranged so that the corrugations thereof correspond with the corrugations 8 of the two heads, so that the 25 walls of the corrugated partitions parallel the corrugated walls of the head, and all of these partitions are spaced apart, forming zig-zag passageways or chambers 13. These partitions are arranged about an inner sleeve 14, which might be formed integral with the partitions, and the ends of 30 this inner sleeve are mounted in the heads 2 and 3. In the zig-zag passages or chambers 13 are situated zig-zag walls 15, provided with angular ribs arranged on axial lines thereby forming a plurality of concentric fluid canals 16, which follow the walls 15 and the corrugations of the partitions 12, so that in reality said canals are zig-zag in 35 two directions, or are produced on transverse and longitudinal angular lines.

40 On the periphery of the corrugated partitions 12 and the heads is mounted a sleeve or jacket 17 which is provided with a number of angular projections 18, the faces 45 thereof paralleling or alining with the faces of the walls 15 to form the outermost canal.

The expansion chamber 7 projects across 50 two sets of these fluid canals, or, in other words, extends across the first two spaces formed between the first two corrugated plates and the head at the inlet end of the motor. The motive element or fluid enters the first set of concentric fluid canals 55 13 through openings 19 in the head 2, said openings communicating with the steam chest 6, and when said motive fluid enters the first set of fluid canals it also enters the second set of concentric fluid canals, 60 through openings 20 formed in the corrugated partition adjacent the head 2, which are in alinement with the openings 19. The motive element in passing through the particularly shaped fluid canals exerts pres-

sure on the walls thereof, and causes the 65 motor to revolve, and after the motive element has passed around the first two sets of concentric canals 13, it enters the expansion chamber 7, with which the first two sets of canals communicate as shown in Fig. 70 4. The motive element or fluid after entering the expansion chambers passes therefrom through the outlet 21 into the third set of fluid canals, and passes entirely 75 around the same until it reaches a point adjacent the openings 20, where each canal ends, the motive fluid being stopped by an abutment or wall 22, and, when the motive fluid reaches this point in each of the canals, it passes into the adjacent canal through 80 openings 23 in the next succeeding corrugated partition and continues this way through all of the canals, the entire length 85 of the motor until it has reached the last set of canals whereby it enters the exhaust chamber 10.

After the motive fluid has entered the exhaust chamber 10, it passes through an exhaust nozzle 24 into a conical chamber 25 carried by the exhaust end wall or head, and 90 arranged on the outside thereof, the exhaust nozzle 24 terminating short of the end walls 26 of the conical chamber 25, whereby the motive fluid contacts with said end wall, and is then caused to travel in the opposite 95 direction through the spiral passageway formed in the conical chamber by the spiral walls 27 finally exhausting from the larger end of the conical chamber into the atmosphere.

100 A shaft 28 passes through the head 3, and is mounted in the inwardly projecting end of the hub 4 formed with the head 2, and the outer end of this shaft and the outwardly projecting end of the hub 4 are 105 mounted in suitable bearings 29 and 30, the latter preferably being a roller bearing.

From the foregoing description it will be seen that as the motive element or fluid is injected into the fluid canals under pressure, said motive fluid will act upon the angular walls and produce sufficient pressure thereon to cause the motor to revolve, and the power thus produced may be utilized in any suitable and well known manner, being transferred from the motor through pulleys and belts or their equivalents.

110 Of course I do not wish to be limited to the exact details of construction as herein shown, as these may be varied within the limits of the appended claims without departing from the spirit of my invention.

Having thus fully described my invention, what I claim as new and useful, is—

125 1. A fluid motor comprising a pair of heads or end walls, an inner sleeve arranged between said heads, a plurality of radially

corrugated partitions spaced apart situated between the heads and surrounding the inner sleeve, an outer sleeve or jacket surrounding the partition and heads, means for dividing the spaces between the corrugated partitions into a plurality of concentric zig-zag fluid canals, and a steam chest having an inlet leading thereto, an outlet leading therefrom communicating with the first two sets 5 of canals, each of the remaining fluid canals being in communication with an adjacent canal.

2. A fluid motor comprising in combination an inlet head having its inner face radially corrugated, a hub carried thereby, one end projecting outwardly and one inwardly, the outwardly projecting end having an inlet passageway therein, a steam chest carried by said head with which the inlet passageway 10 communicates, said head also having openings therein leading from the steam chest to the corrugated face, another head having its face radially corrugated, a shaft passing through the last named head, and mounted in the inner projecting end of the hub of the other head, an inner sleeve mounted between said heads, a plurality of radially corrugated partitions spaced apart and arranged about the inner sleeve between the 15 two heads, an outer sleeve or jacket surrounding said partitions and heads, zig-zag walls arranged between adjacent partitions to form a plurality of zig-zag concentric fluid canals, a wall situated across each of said canals, each of said partitions having a plurality of openings therein adjacent the walls across the canals for forming a communication between adjacent canals, and an exhaust chamber into which the motive 20 fluid passes after encircling the last set of fluid canals.

3. A fluid motor comprising in combination an inlet head having its inner face radially corrugated, a hub carried thereby, one end projecting outwardly and one inwardly, the outwardly projecting end having an inlet passageway therein, a steam chest carried by said head with which the inlet passageway 25 communicates, said head also having openings therein leading from the steam chest to the corrugated face, another head having its face radially corrugated, a shaft passing through the last named head, and mounted in the inner projecting end of the hub of the other head, an inner sleeve mounted between said heads, a plurality of radially corrugated partitions spaced apart and arranged about the inner sleeve between the two heads, an outer sleeve or jacket surrounding 30 said partitions and heads, zig-zag walls arranged between adjacent partitions to form a plurality of zig-zag concentric fluid canals, a wall situated across each of said canals, each of said partitions having a plurality of openings therein adjacent the walls across the canals for forming a communication between adjacent canals, and an exhaust chamber into which the motive 35 fluid passes after encircling the last set of fluid canals.

4. A fluid motor comprising in combination an inlet head having its inner face radially corrugated, a hub carried thereby, one end projecting outwardly and one inwardly, the outwardly projecting end having an inlet passageway therein, a steam chest carried by 40 said head with which the inlet passageway communicates, said head also having openings therein leading from the steam chest to the corrugated face, another head having its face radially corrugated, a shaft passing through the last named head, and mounted in the inner projecting end of the hub of the other head, an inner sleeve mounted between said heads, a plurality of radially corrugated partitions spaced apart and arranged about the inner sleeve between the two heads, zig-zag walls arranged between adjacent partitions to form a plurality of zig-zag concentric fluid canals, a wall situated across each of said canals, each of said partitions having a plurality of openings therein adjacent the walls across the canals for forming a communication between adjacent canals, and an exhaust chamber into which the motive 45 fluid passes after encircling the last set of fluid canals.

5. A fluid motor comprising in combination an inlet head having its inner face radially corrugated, a hub carried thereby, one end projecting outwardly and one inwardly, the outwardly projecting end having an inlet passageway therein, a steam chest carried by said head with which the inlet passageway 50 communicates, said head also having openings therein leading from the steam chest to the corrugated face, another head having its face radially corrugated, a shaft passing through the last named head, and mounted in the inner projecting end of the hub of the other head, an inner sleeve mounted between said heads, a plurality of radially corrugated partitions spaced apart and arranged about the inner sleeve between the two heads, an outer sleeve or jacket surrounding 55 said partitions and heads, zig-zag walls arranged between adjacent partitions to form a plurality of zig-zag concentric fluid canals, a wall situated across each of said canals, each of said partitions having a plurality of openings therein adjacent the walls across the canals for forming a communication between adjacent canals, and an exhaust chamber into which the motive 60 fluid passes after encircling the last set of fluid canals.

minating short of the inner end of said conical chamber, and a spiral arranged within said conical chamber about the exhaust nozzle for giving the motive fluid a whirling motion just before being exhausted to the atmosphere.

In testimony whereof, I have hereunto af-

fixed my signature in the presence of two subscribing witnesses.

FRANK B. HENRY.
